RECLINING CHAIR

Filed March 31, 1928

ATTORNEY

UNITED STATES PATENT OFFICE

CLARENCE B. RECTOR, OF BERKELEY, CALIFORNIA

RECLINING CHAIR

Application filed March 31, 1928. Serial No. 266,201.

The invention relates to an improved chair of the reclining back type.

An object of the invention is to provide a chair of the type described in which the back is normally erect and is arranged to be swung to a position for the reclining of an occupant in the chair by and upon the leaning back of the occupant thereagainst.

Another object of the invention is to provide a chair of the class described having a foot and leg rest arranged to be variably positioned in accordance with the disposal of the chair back.

A further object of the invention is to provide a chair of the class described which is so constructed that a swinging back of the back thereof is increasingly resisted as the reclining position of the back is approached, such being effected without the use of springs or similar appliances.

A still further object of the invention is to provide a chair of the character described which is of extremely simple structure and is adapted for a wide variety of uses.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

Figure 1 is a side view of one embodiment of the chair with the back thereof in erect position.

Figure 2 is a side view of the chair with the back thereof in reclining position.

Figure 3 is a perspective view of the chair with the adjustable parts thereof in an intermediate position.

Essentially, and as shown, the chair of my invention comprises a base portion 4 having rigidly related parts and including side frames 5 on which the remaining chair portions are carried. The chair seat 6 is carried by and between the frames 5 in suspended

relation thereto on members 7 and 8 pivoted to the side edges 9 of the seat adjacent the forward and rear seat edges respectively by means of pivot members 11 and 12, and the members 7 and 8 are in turn pivoted to the frames 5 at points thereof above the pivots 11 and 12 by means of pivot members 13 and 14 respectively. In this manner, the portions of the members 7 between the pivots 11 and 13, and the portion 60 of the members 8 between the pivots 12 and 14 function as suspension links for the seat, it being noted that the lines of the pivots 11 and 13 are substantially parallel to the lines of the pivots 12 and 14 whereby the seat may 65 swing between the frames 5.

It will now be noted that the members 8 extend upwardly from the pivots 14 to cooperatively provide side rails for a back 16 for the chair, and that when said back is in 70 erect position, as shown in Figure 1, the supporting links are arranged to be disposed not far from the vertical. Under these conditions, a person sitting on the seat 6 and leaning against the back 16 is enabled to thereby 75 effect a rearward swinging of the back 16, such movement of the back effecting a slight raising of the seat, though the occupant's center of gravity is arranged to lower slightly as the back swings down. It will be clear that the 80 seat will be moved forwardly, as well as upwardly, as the back is lowered without materially changing the inclination of the seat.

When a person reclining in the chair raises up to relieve the chair back of more or less 85 of his full weight thereon, the chair back will tend to rise, it being noted that the raising of the chair back is effected primarily on account of the weight of the occupant on the chair seat. In this manner, the chair is arranged to automatically set itself in accordance with the position of a person's body 90 therein and a minimum of effort is required on the part of an occupant for disposing the chair in or between its extreme positions. 95

In order to accomplish the foregoing, certain relations have been found desirable between the chair parts. Thus, as has been previously pointed out, the lines joining pivots 11 and 13 are substantially parallel to 100

those joining the pivots 12 and 14. Furthermore, the seat 6 is preferably disposed with its upper side sloping downwardly from the front edge thereof, whereby said seat side makes an acute angle with the chair supporting surface and the lines between the pivots 11 and 12 slope accordingly.

It will furthermore be particularly noted that the distances between the pivots 11 and 13 slightly and measurably exceed those between the pivots 12 and 14 whereby the figure defined by the four pivot points is not a parallelogram and approximates a trapezoid. In this manner, a distortion of this figure occasioned by the swinging back of the chair back tends to change the angular relation of the members 7 and 8. Means are provided for resisting said angular change, such means comprising a link 17 connected between the members 7 and 8 above the pivots 13 and 14 and in nearly parallel relation to the lines of said pivots. Preferably, and as shown, the pivot points of the link 17 cooperate with the pivots 13 and 14 to define a parallelogram. In this manner, a swinging back of the chair back is increasingly resisted, whereby, when the back assumes the position shown in Figure 2, its further movement is substantially stopped by such resistance, it being noted that the various pivotal connections are such as to permit this degree of distortion.

The links 17 are also arranged to provide a positively acting stop means for limiting the lowering of the back 16, and said links are accordingly so disposed and dimensioned that when the back 16 is in lowered position they engage stops 18 provided by the upper end of the frame part 24. Preferably, and as shown, arm rests 19 are mounted on the upper side of the links 17. In this manner, an over straining of the members and pivots forming the sides of the figure defined by the pivots is positively prevented, and the back 16 is arranged to be supported in its fully lowered position.

The members 7, it will now be noted, are continued downwardly from the pivot points 11 thereof and are provided at their bottom extremities with a foot rest member 21 which joins them and is so related to them that when the chair back is up, as in Figure 1, it will engage and rest on the supporting surface for the chair. The integral association with the member 7 of the foot rest thus provided, it will be noted, provides for a forward swinging movement of the latter as the back 16 is swung backwardly, with the members 7 and 8 maintaining their substantially parallel relation. A cross member 22 connects the members 7 above the foot rest 21 whereby a support is provided for an occupant's legs when the chair back is in reclining position.

It will now be noted that the side frames 5 may be of any desired structure. In the present embodiment, these frames are formed

with intersecting members 23 and 24 fixed together at their intersection and arranged to receive the pivots 13 and 14 at their upper end. The lower, or floor engaging, extremities of the members 23 and 24 may directly engage a supporting surface, or may carry rollers 26 for the purpose as shown. The upper ends of the members 24, in the present instance also provide the stops 18, and the frames are held in fixed relation by means of a tie member 26 and the seat 6. It will be noted, however, that any means providing a support for the pivots 13 and 14 in proper relation is intended to come within the scope of the present invention, particular attention being called to the possibility of the installation of the adjustable chair portions between relatively fixed supports, as in a vehicle. And it will be furthermore noted that the back and foot rest structures may vary appreciably from the structures shown without departing from the spirit of the present invention, though their formation to include portions of the members 7 and 8 as shown is a preferred structure, since the number of parts required in fabricating the chair is thereby reduced to a minimum. Obviously, too, chair may be constructed in various sizes.

I claim:

1. In a chair, spaced side frames, a seat, forward and rear links operative to support said seat from and between said frames in suspended and swinging relation, said links being substantially parallel and the forward links being measurably longer than the rear links, and means maintaining said links in said substantially parallel relation during a swinging of said seat.

2. In a chair, spaced side frames, a seat, forward and rear links operative to support said seat from and between said frames in suspended and swinging relation, said links being substantially parallel and the forward links being measurably longer than the rear links, and a member pivotally connected between the front and rear links at a side of the seat operative to resist a swinging of said seat and cooperative with the frame at said side to limit the backward displacement of said chair back.

In testimony whereof I have hereunto set my hand at Oakland, California, this 24th day of March, 1928.

CLARENCE B. RECTOR.
